FASTENING INSERTING MACHINE

Benjamin B. Blanchard, Swampscott, Mass., assignor to United Shoe Machinery Corporation, Flemington, N. J., a corporation of New Jersey

Application May 18, 1945, Serial No. 594,448

10 Claims. (Cl. 1—20)

1

This invention relates to fastening inserting machines, and is herein illustrated as applied to a shoe lasting machine of the type disclosed in United States Letters Patent No. 2,325,100, granted July 27, 1943, on an application filed in my name, although it is to be understood that the invention is not limited to use in machines of that particular character.

It is an object of the present invention generally to improve upon the operation of machines of the type referred to above and specifically to provide improved mechanism for severing fastenings from fastening material, such as wire, after the leading end portion of that material has been fed into fastening forming mechanism in position to be severed and to be formed into a staple. It is a further object of the invention to insure that the work is properly positioned in the machine, particularly that the portion of the shoe bottom where the staple is to be inserted is located in proper position heightwise of the machine so that the wiper with which machines of this type are usually provided will not strike against the edge face of the bottom member of the shoe, for example, the insole, when moving outwardly of the machine to lay the tensioned marginal portion of the shoe upper inwardly over and against the insole.

To this end and in accordance with one feature of the invention, the illustrated machine is provided with novel fastening severing mechanism comprising two relatively movable knives adapted to sever the fed-in leading end portion of the strand of fastening material (wire) from the strand, the fastening severing mechanism including means for moving the two knives as a unit into wire severing position and thereafter for reversing the movement of one of the knives while the other knife remains stationary. Thus, the knife, the movement of which is reversed, is caused to cut the wire against the other stationary knife which acts as a support for the wire in addition to the fastening forming mechanism into which a piece of wire has been fed. Thus any deflection of the fed-in piece of wire during and as a result of the severing operation is effectively prevented. Moreover, the fastening forming mechanism which, as in the machine of the above-mentioned patent, is moved outwardly and inwardly of the machine during one cycle of operations, has its forward movement into staple inserting position divided into two stages separated by a period of dwell, the arrangement being such that, during the first stage of the forward movement of the fasten-

2

ing forming mechanism, the two knives are moved as a unit therewith and that, during the period of dwell, the wire is severed, one knife, as explained, remaining stationary while the other knife cuts the wire in moving rearwardly of the machine. This makes it possible to extend the wire severing operation over a longer period of time during one cycle of operations than was possible heretofore. During the second stage of the forward movement of the fastening forming mechanism the severed piece of wire is formed into a staple and moved into position to be inserted into the work by the driver.

In accordance with another feature of the invention there is provided a movable bottom gage adapted initially to engage the shoe bottom near the edge thereof, the bottom gage being moved inwardly over the shoe bottom by the fastening forming mechanism upon movement of the latter into fastening inserting position. Thus the bottom gage acts to prevent the fastening forming mechanism from striking against the edge face of the insole in moving into its fastening inserting position over the shoe bottom.

These and other features of the invention will now be described in detail with reference to the accompanying drawings and will be pointed out in the appended claims.

In the drawings,

30 Fig. 1 is a right-hand side elevation of the head of a machine in which the present invention is illustrated as embodied, certain unessential parts being broken away;

35 Fig. 2 is a right-hand side elevation of the fastening forming mechanism, its actuating mechanism and mechanism for actuating the wire severing knives, the machine parts being shown in their initial positions;

40 Fig. 3 is a right-hand side elevation of the wire severing mechanism and part of its actuating mechanism, the machine parts being shown in their initial positions;

45 Fig. 4 is a front elevation of the machine head with unessential parts broken away;

Fig. 5 is a right-hand side elevation of the bottom gage and part of the fastening forming mechanism in its operative staple inserting position;

50 Fig. 6 is an exploded view of the wire severing knives and staple formers;

Fig. 7 is a right-hand side elevation of the wire severing mechanism and its actuating mechanism, the machine parts being shown in the positions which they assume immediately after the wire severing operation;

Fig. 8 is an exploded view of the slides carrying the wire severing knives and of parts of their actuating levers; and

Fig. 9 is a schematic illustration of the mechanism for actuating the wire severing knives, the principal parts of that mechanism being shown in different positions during one cycle of operations.

As previously stated, the invention is illustrated as embodied in a machine of the type disclosed in my above-mentioned Letters Patent and accordingly only so much of that machine will be disclosed herein in detail as is necessary for an understanding of the present invention.

General organization

The machine illustrated in the drawings, the same as the machine disclosed in the above-mentioned patent, is adapted to tension progressively a shoe upper U (Figs. 2 and 5) over a last L along opposite sides thereof and, if desired, around the toe end of the last, to wipe the marginal portion of the upper inwardly over a sole member, such as an insole I, provided on the bottom of the last L, and to secure that marginal portion in overlasted relation to the insole, by fastenings, such as wire staples. The work to be operated upon, and comprising the upper U, the last L and the insole I, is held in the operator's hands and successive portions of the margin of the shoe upper are presented to the operating instrumentalities of the machine to be tensioned over the last and to be secured in lasted relation to the insole by the staples. To determine the proper position of the work with relation to the operating instrumentalities of the machine, the latter is provided with a shoe bottom rest 20 (Fig. 1) which is secured to the machine frame, a thin edge gage 22 which is employed when lasting the sides of the work, and a thick edge gage 24 which is employed when lasting around the toe end of the work. As in the prior machine, the thin edge gage 22 is secured to a bracket 26 fast on the machine frame, whereas the thick edge gage 24 is slidably mounted on the bracket 26 and is manually movable into and out of operative position for use in place of the thin edge gage 22.

In addition to the two edge gages 22 and 24 there is provided a movable bottom gage 28 (Figs. 1, 2, 4 and 5), the construction and operation of which will be described later. In its initial position the bottom gage 28 positions that portion of the shoe bottom, near the edge thereof, where a fastening is to be inserted accurately heightwise of the machine.

For tensioning the upper heightwise of the last there is provided a gripper 30 (Fig. 1) and for laying the marginal portion of the upper inwardly over the insole I there is provided a wiper 32 which is arranged for movement outwardly of the machine and inwardly over the shoe bottom, the wiper 32 also functioning as a fastening transferring throat since it serves the additional purpose of moving the formed fastening into position to be inserted by a driver 34. To prevent the wiper or throat 32 on outward movement from abutting the insole edge face, the bottom gage 28 is provided. In moving outwardly of the machine, the wiper 32 is caused to engage the bottom gage 28 and to move the bottom gage outwardly of the machine and inwardly over the shoe bottom.

The fastening inserted by the machine is a staple which is formed in the machine from a piece of wire severed by a wire severing mechan-

ism from the leading end portion of a wire strand after a predetermined and adjustable length of wire has been fed by a wire feeding mechanism into a fastening forming mechanism. The wire feeding mechanism (not shown) is substantially like the wire feeding mechanism disclosed in the above mentioned patent. This mechanism serves intermittently to advance the wire strand a predetermined length through a flexible wire guiding conduit 36 (Figs. 4 and 6) into the fastening forming mechanism.

The fastening forming mechanism is substantially the same as the fastening forming mechanism disclosed in the above-mentioned patent.

15 Its main elements are the already mentioned wiper or throat 32 to which is imparted one horizontal reciprocation outwardly and inwardly of the machine during one cycle of operations, an inside staple former 38 and an outside staple former 40 (Figs. 1, 2, 5 and 6). The fastening forming mechanism, including the throat 32 and the formers 38 and 40, is carried on a slide 42, hereinafter called the "throat slide." The throat slide 42 is movable inwardly and outwardly of the machine in a guideway provided in the machine frame.

20 The wire severing mechanism comprises primarily two knives, namely, a top knife 44 (Figs. 3, 4, 6, 7 and 8) mounted for movement in a direction parallel to the direction of movement of the throat slide 42, and a bottom knife 46 mounted for movement independently from the top knife 44, also in a direction parallel to the direction of movement of the throat slide 42. The 25 entire wire severing mechanism is supported on a slide 48 (Figs. 2, 3, 4 and 7) which is adjustable in a direction transversely of the direction of movement of the throat slide 42 to vary the length of the wire to be severed and thus the 30 length of the staple to be formed. The slide 48, which may be referred to as the transverse slide, is mounted for movement on a bracket 50 secured to the machine frame.

The fastening forming and inserting mechanism

35 As in the machine of the above-mentioned patent, the driver 34 is secured to the lower end of a driver bar 52 (Fig. 1) which is raised by a cam (not shown) against the resistance of a torsion spring (not shown) and which is released by the cam to the action of the loaded torsion spring to insert a staple into the work, the staple being contained in the throat or wiper 32 and the staple inserting movement of the driver taking place after the slide 42 and the throat 32 have completed their forward movements outwardly of the machine during which the wiper or throat 32 has laid the tensioned marginal portion of the upper U inwardly over and flat against the insole I. As will be explained the wiper 32 has a passageway for guiding the driver 34 and the staple. In order to align the driver 34 with the passageway of the wiper 32, the throat slide 42 is provided with an adjustable abutment 54 (Figs. 1 and 2) engaging the driver bar 52 on outward movement of the throat slide 42 and swinging the driver bar outwardly of the machine. To determine the foremost position of the driver bar 52 in the machine there is provided a bar 56 adjustably secured to the machine frame and provided with a laterally deflected end portion acting as a stop for the driver bar 52.

40 The inside former 38 and the outside former 40 are mounted and actuated in the following manner. As stated, both formers are carried by the

throat slide 42, the slide also carrying part of the mechanism for operating the formers, namely for gripping the wire before the wire is severed and thereafter for forming a staple from the severed piece of wire. Conveniently the forward movement of the throat slide 42 is utilized to operate the formers and in order that the throat slide 42 may receive a reciprocatory movement of sufficient extent for the purpose in view, it is formed in two parts connected together by a lever 58 (Fig. 1) fulcrumed to the machine frame. The lever is pivoted at its upper end to the forward portion of the slide 42 and is pivoted substantially midway between its ends to the rear portion 60 of the slide 42 which is reciprocated once in each cycle of operations of the machine by the usual lever 62 and cam 64. However, the cam is so designed that the forward movement of the throat slide 42 is not continuous but takes place in two stages separated by a period of dwell, the arrangement being such that the two formers 38 and 40 are caused to grip the wire between them during the first stage of movement of the throat slide 42, that the wire is severed during the dwell of the throat slide and that the formers 38 and 40 are operated to form the staple during the second stage of the forward movement of the throat slide 42.

The outside former 40 is carried on the lower end of a slide 66 (Figs. 1 and 2) arranged for movement heightwise of the machine in an inclined guideway 68 which is formed in the forward end of the throat slide 42, the slide 66 having a yielding pivotal connection, as in the machine of the above mentioned patent, with the forward end of a cam lever 70 pivotally secured to the throat slide 42 and carrying at its rear end a roll 72 engaging a cam track 74 provided in a bracket secured to the machine frame. The cam track 74 is so shaped that, during the first stage of the forward movement of the throat slide 42, the outside former 40 is first yieldingly lowered to grip the fed-in piece of wire against the inside former 38.

The inside former 38 is slidably mounted in a guideway formed in the forward end of the throat slide 42, the inside former being arranged for movement into and out of operative relation to the outside former 40 and being normally held in its forward position by a torsion spring 76 (Fig. 4) which is coiled about the right end portion of a short shaft 78 mounted to turn in the forward end of the throat slide 42. The shaft 78 has formed integrally with it a downwardly extending arm 80 (Fig. 2) the rounded lower end of which extends into a recess in the inside former 38 and which serves to move the inside former. Clamped to the right-hand end of the shaft 78 by means of a nut 82 is an arm 84 which is provided with a rearward extension 86 acting by engagement with an adjustable screw 88 carried by the throat slide 42 to limit and determine the forward position of the inside former 38. The arm 84 extends forwardly and upwardly, as shown in Fig. 2, and lies in the path of movement of a roll 90 carried by a depending portion 92 on the front arm of the cam lever 70.

The outside former 40 is provided with a passage 94 (Fig. 6) for the driver 34 which passage is in alinement with a similar driver passage 96 (Figs. 2 and 5) formed in the wiper or throat 32. The inside former 38 normally extends into position to cooperate with the outside former 40 and to act as a support for the fed-in portion of the wire strand. The inside former 38 is provided

with a horizontal slot 98 (Fig. 6) ending in an enlarged round portion 100 through which the wire is fed. The outside former 40 has a horizontal recess 102 cooperating with the slot 98 in the initial position of both formers to guide the wire when it is being fed into the fastening forming mechanism. As stated, the shape of the cam track 74 is preferably such that substantially at the beginning of the forward movement of the throat slide 42, the cam lever 70 is swung in a counterclockwise direction, as viewed in Fig. 1, to impart downward movement to the slide 66 so as to cause the outside former 40 yieldingly to clamp the fed-in portion of wire against the inside former 38 preparatory to the wire severing operation. Moreover, as a result of this movement of the cam lever 70, the inside former 38 is slightly retracted, thus bringing the wire into the narrow forward portion of the slot 98. Thereafter the two formers dwell as the throat slide 42 dwells during its forward movement and as the wire is being severed. Then, during the second stage of the forward movement of the throat slide 42, the staple is formed as already mentioned, the outside former 40 being moved all the way down on top of a shoulder 104 (Figs. 2, 4 and 5) of the wiper or throat 32 and the inside former 38 being fully retracted out of the way of the driver 34 which descends to drive the formed staple through the upper U and the insole I, the legs of the staple being clenched against a metal plate P with which the bottom of the last L is provided.

It will be understood that with the outside former 40 in its lowermost position, there is provided a substantially continuous passage through it and through the wiper 32 for the staple and the driver 34, and that the staple and driver passages are moved into alinement with the driver 34, the position of which, as explained, is determined by the front end of the bar 56.

The wire feeding mechanism

The wire feeding mechanism, as already explained, is substantially the same as the wire feeding mechanism disclosed in the above-mentioned patent. The mechanism includes, as in the prior machine, an adjustable stop screw 106 (Fig. 4) and an arm 108 which is part of a bell-crank lever, the screw 106 acting to limit the extent of swinging movement of the bell-crank lever under the influence of a spring (not shown) thus stopping the operation of the feed wheel (not shown) when a predetermined length of wire has been fed into position to be acted upon by the inside and outside formers. The stop screw 106 is carried by a plunger 110 which is vertically movable in a recess in the machine frame, a locknut 112 being provided for holding the screw 106 in adjusted position relatively to the plunger 110. The plunger 110 rests on the edge face 114 of a segment 116 which is secured to the left-hand end portion (Fig. 4) of a shaft 118 mounted in a bearing in the above-mentioned bracket 50. The edge face 114 of the segment 116 is eccentric to the axis of the shaft 118 and, in order that the segment may be rotated quickly to vary the heightwise position of the plunger 110 and thus of the stop screw 106, and accordingly to vary the length of wire fed and the length of staples to be formed, there is fast to the right-hand end portion of the shaft 118 a hand lever 120 (Figs. 1, 2, 4). For determining the proper limits of movement of the hand lever 120 in opposite directions to vary the position of the stop screw 106, there are provided

stops 122, 124 adjustably secured in a curved guideway 126 formed in a bracket 128 secured to the bracket 50.

The wire severing mechanism

As previously explained, the wire severing mechanism includes two knives 44 and 46 which are carried by the transverse slide 48. The transverse slide 48 is adjusted whenever the length of wire fed to form staples is varied, this to insure that the knives 44 and 46 will be positioned in proper relation to the inside former 38 and the outside former 40 so that the legs of each staple, when formed from each severed piece of wire will be equally long. To this end there is pivotally secured to the bracket 50 a two-armed lever 130 (Fig. 4), the forked upper arm 132 of which engages a pin 134 carried by the slide 48. The lower arm 136 of the lever 130 carries a pin 138 which engages a cam groove 140 provided in the segment 116. The shape of the cam groove 140 is such that in all positions of adjustment of the segment 116 and the stop screw 106, the knives 44 and 46 will be positioned in proper relation to the inside and outside formers.

To aid in keeping the slide 48 in whatever position of adjustment it may be and to prevent backlash there is provided a spring 142 (Fig. 4) seated in a bore 144 provided in the bracket 50. The left-hand end (Fig. 4) of the spring 142 bears against a plate 146 secured to the transverse slide 48 by a screw 148. Thus the spring 142 tends to displace the transverse slide 48 toward the left of Fig. 4.

As illustrated in Fig. 6 the bottom knife 46 has provided through it a wire guiding passage 150 into which leads the conduit 36 after having passed through a wire straightener 152 of conventional design. Conveniently the wire supply is coiled up on a reel (not shown) mounted on the machine frame. The wire guiding passage 150 emerges from an inclined upper face of the bottom knife 46 with which cooperates a similarly inclined lower face of the top knife 44 to sever the wire after it has been fed into the fastening forming mechanism. The bottom knife 46 has a guide rib 154 which fits into a guideway provided in a depending portion 156 (Figs. 3, 7 and 8) of a bottom knife slide 158 to which the bottom knife is secured by a screw 159. The slide 158 is constrained to move in a horizontal direction parallel to the direction of movement of the throat slide 42 and to this end the slide 158 has a rearwardly extending cylindrical stem 160 engaged in a bore 162 provided in a top knife slide 164. The slide 164 is substantially block-shaped and is movable in a guideway 166 provided in the transverse slide 48 in a direction parallel to the direction of movement of the throat slide 42. The guideway 166 for the top knife slide 164 is formed in part by a gib 168 secured to the right-hand end face (Fig. 4) of the transverse slide 48 by screws 170. The bottom knife slide 158 is prevented from turning about the axis of its stem 160 by the provision of a square recess 172 in the top knife slide 164 into which recess snugly fits a square portion 174 of the bottom knife slide 158. The top knife 44 has a guide rib 176 (Fig. 6) which fits into a vertical guideway provided in the top knife slide 164, the top knife 44 being secured to its slide 164 by a screw 178. The two knives 44 and 46 are operated by common mechanism first to move as a unit with the throat slide 42 during the first stage of the forward movement of the latter to keep the knives alined with the in-

side and outside formers after the wire has been fed therethrough. Then, during the period of dwell in the forward movement of the throat slide 42, the two knives 44 and 46 are moved with relation to each other to sever the piece of wire fed into the fastening forming mechanism from the wire strand preparatory to the forming of a staple from that piece of wire. More particularly, in the wire severing operation, the top knife 44 remains stationary and the forward movement of the bottom knife 46 is reversed to cut against the top knife. To this end there is provided in the upper portion of the transverse slide 48 a bearing 180 (Figs. 2, 4 and 7) for a stub shaft 182 on which is mounted a two-armed rocking lever 184. The left arm 186 of the rocking lever 184 is provided with a cam groove 188 designed to impart to the bottom knife 46 its particular movement. The right arm 190 of the rocking lever 184 also is provided with a cam groove 192 which is designed to operate the top knife 44. In particular the bottom knife 46 is operated by a substantially vertical lever 194 pivotally secured at 196 to the transverse slide 48 and carrying at its upper end a cam roll 198 which is engaged in the cam groove 188. The lever 194 is split at its lower end to carry a stud 200 (Fig. 8) which extends into a block 202 carried in the fork-shaped front end of the bottom knife slide 158. The cam groove 188 is so designed that, during the forward movement of the throat slide 42, the bottom knife 46 is first moved as a unit with the throat slide, whereupon its movement is reversed while the throat slide dwells. To actuate the top knife 44 there is provided a substantially vertical lever 204 pivoted at 206 to the transverse slide 48 and carrying at its upper end a roll engaging in the cam groove 192. The lower end of the lever 204 is split and carries a stud 208 (Fig. 8) extending into a block 209. The block 209 fits into a guideway provided in one side of the top knife slide 164. The design of the cam groove 192 is such that the top knife 44 is moved with the throat slide 42 during the first stage of the forward movement of the latter and then is caused to dwell during the dwell of the throat slide.

The rocking lever 184 is oscillated about the shaft 182 in time relation to the movement of the throat slide 42 by the vertical arm of a bell crank lever 210 (Figs. 2, 4 and 7) which has a fork-shaped upper end pivotally connected at 212 to an upwardly extending arm 214 of the rocking lever 184. The bell crank lever 210 is fulcrumed on a shaft 216 mounted in bearings provided in the transverse slide 48. A rearwardly and upwardly extending arm of the bell crank lever 210 has a forked end 218 (Fig. 4) which carries a transverse pin 220 engaged by the fork-shaped end of a cam-operated lever 222. The lever 222 is pivotally secured at 224 to the machine frame and carries a roll 226 which engages a cam groove 228 in a cam disk 230. The cam disk 230 is rotatable on a shaft 232 mounted in the machine frame, it corresponding to and being actuated like the cam disk in the machine of the above-mentioned patent from which power for operating the wire turning mechanism is derived. The wire turning mechanism is not employed in the present machine. It is to be understood that the cam groove 228 is designed differently to impart the proper motions to the rocking lever 184 and thereby to the knives 44 and 46. The forked end 218 of the bell crank lever 210 is sufficiently wide and the transverse pin 220 is sufficiently long to

permit the transverse adjustment of the bell crank lever 210 with the transverse slide 48, this adjustment taking place with relation to the cam operated lever 222.

The chief component parts of the above described mechanism for actuating the wire severing knives and their motions are schematically illustrated in Fig. 9 of the drawings. These parts are the cam operated lever 222, the bell crank lever 210, the rocking lever 184 with its upwardly extending arm 214 and the two cam grooves 188 and 192, the lever 194 actuating the bottom knife slide 158 and deriving its motion from the cam groove 188, and the lever 204 actuating the top knife slide 164 and deriving its motion from the cam groove 192. The cam operated lever 222, by which this mechanism is set into motion, is shown in three different positions indicated by the reference characters *a*, *b* and *c* and distinguished from each other in that the initial position *a* is shown in full lines, the intermediate position *b* (occupied after the first stage of the forward motion of the throat slide 42 and before the wire severing operation) is shown in dash lines, and the final position *c* (occupied at the conclusion of the wire severing operation) is shown in dotted lines. The other machine parts illustrated in Fig. 9 (with the exception of the rocking lever 184) are shown in three different positions corresponding to the positions *a*, *b* and *c* of the cam operated lever 222. In particular, it will be noted that during and as a result of the movement of the cam operated lever 222 from the position *a* to the position *b*, the levers 194 and 204 actuating the knife slides 158 and 164 move equal distances from the positions *a'* to *b'* and *a''* to *b''* respectively. This movement of the levers 194 and 204 is concomitant with the first stage of the forward movement of the throat slide 42. While the throat slide 42 dwells thereafter, the lever 222 moves from the positions *b* to *c*, causing a reverse movement of the lower end of the lever 194 from the positions *b'* to *c'*. The lower end of the lever 204, however, remains stationary at that time. This reverse movement of the lever 194 causes a reverse movement of the bottom knife 46 toward the then stationary top knife 44 during the course of which movement the wire is severed.

The bottom gage mechanism

The bottom gage 28, as already mentioned, is movable inwardly and outwardly of the machine. It extends laterally from a slide 234 to which it is secured. The slide 234 has a T-shaped guide rib 235 (Fig. 4) fitting into a T-shaped horizontal guideway 238 provided in the bracket 50 so that the slide 234 with its bottom gage 28 may be moved with relation to the bracket 50. The slide 234 has extending laterally therefrom a pin 240 (Figs. 2 and 4) to which is secured the front end of a spring 242 the rear end of which is anchored to the machine frame. The spring 242 thus tends to pull the slide 234 inwardly of the machine until a downward projection 244 of the slide 234 engages a lateral projection 246 provided on a rod 248 mounted for adjustment in a horizontal bore provided in the machine frame and held in adjusted position by a set screw 250. When the throat slide 42 and with it the wiper or throat 32 is advanced outwardly of the machine, it engages the bottom gage 28 and pushes it and its slide 234 outwardly of the machine and inwardly over the shoe bottom. When the wiper 32 is again retracted, the

spring 242 becomes active to pull the slide 234 and the bottom gage 28 back into their initial positions.

Novel features of the bottom gage mechanism herein disclosed are claimed in a divisional application Serial No. 770,005, filed August 22, 1947.

Operation

In the initial inoperative position of the machine parts the throat slide 42 is in its rearward position, the outside former 40 is in its uppermost position and the inside former 38 is in its forward position in cooperative relation to the outside former. The driver 34 is in its upper position. Both the bottom knife slide 158 and the top knife slide 164 are in their retracted positions. Before starting the operation of the machine the operator presents the work to the machine in a position determined by the edge gage 22 (or the edge gage 24), the bottom rest 20 and the bottom gage 28. The marginal portion of the shoe upper U is inserted between the open jaws of the gripper 30. After initiation of the machine operation, a piece of wire is fed through the bottom knife passage 150 into and through the recess 102 of the outside former 40 and also through the round portion 100 of the slot 98 of the inside former 38. This consumes about 100° of one cycle of operations. During the next 40° of the cycle the throat slide 42 is advanced slightly about $\frac{1}{4}$ " with the result that the outside former 40 is lowered somewhat (about $\frac{1}{16}$ ") to grip the fed-in piece of wire and that the inside former 38 is slightly retracted (about $\frac{3}{64}$ ") to bring the wire into the front portion of the slot 98. At the same time, both the bottom knife slide 158 and the top knife slide 164 are advanced about $\frac{1}{4}$ " to keep the knives 44 and 46 in alignment with the staple formers 38 and 40. Then the throat slide 42 dwells for a further 40° of the cycle, with the result that the staple formers 38 and 40 dwell. The top knife slide 164 (and thus the top knife 44) also dwells during that period but the bottom knife slide 158 is reversed to cause the bottom knife 46 to sever the fed-in piece of wire by cutting rearwardly of the machine against the stationary top knife 44. Both knives, after the wire has been severed, dwell for a further 60° of the cycle during which the advance of the throat slide 42 into its operative position is resumed, as a result of which the wiper 32 lays the margin of the upper which, in the meantime has been tensioned by the gripper, inwardly over and against the insole I, thereby also pushing the bottom gage 28 inwardly over the shoe bottom. As a further result of this forward movement of the throat slide 42, the outside former 40 is caused completely to move into its lowermost position, thus bending the severed piece of wire about the inside former 38 and forming the staple, the inside former 38 being ultimately retracted into its rearmost operative position out of the path of movement of the driver 34.

During the succeeding 60° of the cycle the driver 34 descends to drive the staple into the work while the outside former stays down and the inside former is kept retracted. The driver then is immediately moved back to its elevated position. During this period the knife slides begin their rearward movements into their initial retracted positions and finally the throat slide 42 goes back thereby elevating the outside former and advancing the inside former to its ini-

tial position in operative relation to the outside former and in readiness to receive a new piece of wire at the beginning of the next cycle of operations.

Having described the invention, what I claim as new and desire to secure by Letters Patent of the United States is:

1. In a fastening inserting machine, fastening forming mechanism, a fastening inserting driver cooperating therewith, means including two relatively movable knives adapted to sever a fastening from fastening material fed into said mechanism, and means for moving the two knives as a unit into fastening severing position and thereafter for reversing the movement of one of the knives while holding the other knife stationary thereby to sever the fastening from the fastening material.

2. In a fastening inserting machine, fastening forming mechanism movable relatively to a piece of work presented to the machine into a position in which a fastening contained therein may be inserted into the work, a fastening inserting driver cooperating with said mechanism, means including two relatively movable knives adapted to sever a fastening from fastening material fed into said mechanism, and means for moving the two knives as a unit into fastening severing position and in the same direction as the direction of movements of the fastening forming mechanism into fastening inserting position and thereafter for reversing the movement of one of the knives while holding the other knife stationary thereby to sever the fastening from the fastening material.

3. In a fastening inserting machine, fastening forming mechanism movable relatively to a piece of work presented to the machine into a position in which a fastening contained therein may be inserted into the work, means for moving said mechanism, means including two relatively movable knives adapted to sever a fastening from fastening material fed into said mechanism, and means separate from said moving means for moving the two knives as a unit into fastening severing position and thereafter for reversing the movement of one of the knives while holding the other knife stationary thereby to sever the fastening from the fastening material.

4. In a fastening inserting machine, fastening forming mechanism movable relatively to a piece of work presented to the machine into a position in which a fastening contained therein may be inserted into the work, means for moving said mechanism into fastening inserting position in two stages separated by a period of dwell, means including two relatively movable knives adapted to sever a fastening from fastening material fed into said mechanism, and means for moving both knives as a unit into fastening severing position during the first stage of the movement of said mechanism and thereafter and during the period of dwell of said mechanism for reversing the movement of one of the knives while holding the other knife stationary thereby to sever the fastening from the fastening material.

5. In a fastening inserting machine, fastening forming mechanism movable relatively to a piece of work presented to the machine into a position in which a fastening contained therein may be inserted into the work, means for moving said mechanism into fastening inserting position in two stages separated by a period of dwell, means including two relatively movable knives adapted

to sever a fastening from fastening material fed into said mechanism, and means separate from said moving means for moving both knives as a unit into fastening severing position and in the same direction as the direction of movement of the fastening forming mechanism into fastening inserting position during the first stage of the movement of said mechanism and thereafter and during the period of dwell of said mechanism for reversing the movement of one of the knives while holding the other knife stationary thereby to sever the fastening from the fastening material.

6. In a fastening inserting machine, fastening forming mechanism movable relatively to a piece of work presented to the machine into a position in which a fastening contained therein may be inserted into the work, means for moving said mechanism into fastening inserting position in two stages separated by a period of dwell, means including two relatively movable knives adapted to sever a fastening from fastening material fed into said mechanism, means for moving said fastening forming mechanism, and means separate from said moving means for moving both knives as a unit into fastening severing position and in the same direction as the direction of movement of the fastening forming mechanism into a fastening inserting position during the first stage of movement of said mechanism and thereafter and during the period of dwell of said mechanism for reversing the movement of the knives while holding the other knife stationary thereby to sever the fastening from the fastening material.

7. In a fastening inserting machine, fastening forming mechanism movable relatively to a piece of work presented to the machine into a position in which a fastening contained therein may be inserted into the work, the fastening forming mechanism including an inside former and an outside former, means for moving the fastening forming mechanism into fastening inserting position in two stages separated by a period of dwell, means including two relatively movable knives adapted to sever a fastening from fastening material fed into said mechanism, means for moving the two formers with relation to each other during the first stage of movement of the fastening forming mechanism to cause the formers to grip the fastening material between them, means for moving both knives as a unit into fastening severing position during the first stage of movement of the fastening forming mechanism and thereafter and during the period of dwell for reversing the movement of one of the knives while holding the other knife stationary thereby to sever a fastening from the fastening material, the means for moving the two formers being adapted to resume the relative movements of said formers during the second stage of the movement of said mechanism thereby to form the severed fastening.

8. In a fastening inserting machine, fastening forming mechanism, a fastening inserting driver cooperating therewith, a knife adapted to present fastening material in a position to be cut, another knife cooperating with the first mentioned knife, and common actuating means for both knives adapted to move the knives as a unit into fastening severing position and thereafter to reverse the movement of one of the knives while holding the other knife stationary thereby to sever a fastening from the fastening material.

9. In a fastening inserting machine, fastening forming mechanism, a fastening inserting driver cooperating therewith, a knife adapted to present

fastening material in a position to be cut, another knife cooperating with the first-mentioned knife to sever the fastening material, a two-armed rocking lever for actuating the two knives, cam portions provided in the opposite arms of said lever, and separate mechanisms connected to the knives and separately operated by said cam portions.

10. In a fastening inserting machine, fastening forming mechanism movable relatively to a piece of work presented to the machine into a position in which a fastening contained therein may be inserted into the work, the fastening forming mechanism including an inside staple former having a slot provided with a widened wire receiving portion and an outside staple former provided with a wire receiving recess, means for initially positioning the inside former and the outside former to cause said recess to cooperate with said wire receiving portion to guide the wire when being fed in, and for slightly retracting the inside former after a length of wire has been fed to cause the wire to be located in the front portion of said slot and simultaneously for depressing the

outside former to grip the wire, and means for severing the fastening from said wire.

BENJAMIN B. BLANCHARD.
